UNITED STATES PATENT OFFICE

2,508,248

COMBINED ICE TANK BRACING FRAME AND
ICE HOPPER FOR REFRIGERATOR CARSHoward A. Glenn, Oak Park, and Jack K.
Dromgold, Chicago, Ill.

Application February 28, 1948, Serial No. 12,074

13 Claims. (Cl. 62—19)

1

The principal objects of this invention are: To facilitate and speed up the icing of brine tank cars; to protect the refrigerated area from loss of cold air during those necessary icing operations; to reduce the cost of maintenance; and, generally, to improve brine tank cars in the area above the tanks.

Further objects and advantages of the invention will appear as the disclosure proceeds and the description is read in connection with the accompanying drawings showing the preferred embodiment of the invention, in which:

Fig. 1 is a cross section of the upper portion of a refrigerator car through the brine tanks showing the improved tank bracing frame and ice hoppers embodying the invention in heavy lines;

Fig. 2 is an inverted plan view looking upwardly at the bracing frame in Fig. 1;

Fig. 3 is a perspective view of an article of manufacture composed of the improved bracing frame and ice hoppers; and

Fig. 4 is a transverse section taken on the line 4—4 of Fig. 1.

In Fig. 1, 10 indicates generally the side wall and 11 the roof of a refrigerator car equipped with hatchways 12 at each side of a running board 13 and communicating with four brine tanks 14 grouped crosswise to the end portion of a car.

The bracing frame for the tanks includes spaced bars 15 extending crosswise to the car and connected at their ends by crossbars 16. Adjacent to the middle portion of the bars 15, they are connected by other crossbars 17, and between those bars 17 and the end bars 16 the bars 15 are connected by still other bars 18.

In this preferred embodiment, the bars 15 are of angle section with the vertical flange 19 of each turned downwardly and adapted to lie alongside the respective front and back walls of the tanks 14, as best shown in Fig. 4. The crossbars 16, 17, and 18 are also of angle section with their vertical flanges extending downwardly inside of the upper ends of the tanks 14 adjacent to the side walls thereof, as best shown in Fig. 1.

As best shown in Figs. 3 and 4, the vertical flanges are cut away on an incline, and the ends of the horizontal flanges of the angles 16, 17 and 18 are welded to the inner edges of the horizontal flanges 21 of the angles 15 and to overlapping gusset plates 22, which extend across the flanges 21 and a suitable length along the top of the adjoining cross pieces.

The hopper or hoppers in this preferred form include spaced side plates 24 and 25 extending

2

crosswise to the car along the inner edges of the bars 15 and inclining outwardly and upwardly, as best shown in Fig. 4. They are connected at their ends, which are cut to correspond, with inwardly and upwardly inclined plates 26 and 27. The intermediate portions of the plates 24 and 25 are connected by upwardly and outwardly inclined plates 28 and 29. As here shown, the plates 24 and 25 are notched to fit over the crossbars 17 and 18, and are welded to both the horizontal and the vertical flanges of those bars.

The end plates 26 and 27 have vertical portions or flanges 31 lying along the inside of the vertical angles of the bars 16 and welded thereto. The lower edges of the plates 28 and 29 have similar vertical portions or flanges 32, which are alongside of and welded to the vertical flanges 20 of the crossbars 17. The lower edges of the plates 24 and 25 may also be welded along the inner edges of the horizontal flanges of the bars 15, or otherwise made to join them tightly.

As here shown, the bars 17 and 18 are made of angles with their horizontal flanges welded together to form channels, and actual channel sections of corresponding width may be used instead.

The horizontal flanges of the end crossbars 16 are provided with openings 35 by which the combined bracing frame and ice hopper may be secured to the side walls of the car, in this illustration by bolting to the angles 36.

The actual design and construction of refrigerator cars varies greatly (Car Builders' Cyclopedias, 1937, p. 167), and the general illustration here shown is merely for the purpose of showing the atmosphere in which the improvements find their greatest use. However, it should be emphasized that those improvements are especially suited for steel car construction.

The manner of assembly with the car and the brine tanks will vary with personal preference and conditions, but a suitable procedure is to emplace the commercial units substantially as illustrated in Fig. 3 within the car in the position shown in Fig. 1 and make it fast. Then, the brine tanks are brought upwardly into interlocked position with the bracing frame and seated on the support, which is ordinarily composed of two angles (not shown) with their horizontal flanges turned toward each other and receiving the bottoms of the tanks.

Attention is particularly drawn to the interlocking arrangement between the bracing frame and the upper ends of the tanks, whereby the vertical angles of the bars 15 secure the upper

ends of the tanks against moving fore and aft, and the vertical flanges of the other bars 16, 17, and 18 hold the tanks against movement crosswise to the car. The lower and delivery ends of the hoppers formed by the plates 24, 25, 26, 27, 28, and 29 are tightly sealed to the frame, and the relation between the vertical flanges of the bars of the frame and the upper ends of the tanks make a good seal with the tanks. The upper edges of the hoppers formed by the plates 24, 25, 26, 27, and 28 fit nicely over the lower edges 39 of the hatchway liners 40. This neat fitting makes an effective seal for the cold air within the car, and there is no escape during the icing operations when the hatchways are open, except the small area exposed through the hatchways.

Attention is also particularly invited to the ample and convenient passageway for the ice formed by the hoppers from the hatchways into the intermediate tanks as well as the outside tanks.

The tanks can be readily removed and replaced from below, and when removed the combined bracing frame and hoppers may be removed and replaced. Ordinarily, the end roofing section is the last to go on the car, and the final arrangement of the insulation beneath it is conveniently made just before that section is put on.

The insulation has been purposely omitted, in the interest of clearness of the drawing.

We claim:

1. In a refrigerator car having ice tanks and hatches therefor, a bracing frame adapted to extend crosswise to the car and beneath the hatches and including spaced bars adapted to hold the tanks against movement lengthwise to the car, and other spaced bars spanning the first mentioned bars, secured thereto, and adapted to hold the tanks against movement crosswise to the car, and a hopper supported on said frame for communication with the hatches and with the ice tanks.

2. In a refrigerator car having ice tanks and hatches therefor, a bracing frame adapted to extend crosswise to the car and beneath the hatches and including spaced bars having vertical flanges adapted to hold the tanks against movement lengthwise to the car, and other bars spanning the first mentioned bars, secured thereto, and having vertical flanges adapted to hold the tanks against movement crosswise to the car, and a hopper supported on said frame and communicating at its top with the hatches and at its bottom with the tops of the tanks.

3. In a refrigerator car having ice tanks, a bracing frame adapted to extend crosswise to the car and beneath the hatches and including spaced bars adapted to hold the tanks against movement lengthwise to the car, other spaced bars spanning the first mentioned bars, secured thereto, and adapted to hold the tanks against movement crosswise to the car, and a hopper for the tanks including inclined plates secured to the frame along the first mentioned bars and other inclined plates secured to the first mentioned inclined plates and to some of the other spaced bars.

4. In a refrigerator car having ice tanks, a bracing frame adapted to extend crosswise to the car and beneath the hatches and including spaced bars having vertical flanges adapted to hold the tanks against movement lengthwise to the car and other bars spanning the first mentioned bars, secured thereto, and having vertical flanges adapted to hold the tanks against movement

crosswise to the car, and a hopper for the tanks including inclined plates secured to the frame along the first mentioned bars and other inclined plates secured to the first mentioned inclined plates and to some of the other spaced bars.

5. In a hopper for refrigerator cars having ice tanks and hatches therefor, spaced outwardly and upwardly inclined sheets adapted to extend crosswise to the car below the hatches and above the ice tanks, inwardly and upwardly inclined plates connecting the end portions of the first mentioned plates, and outwardly and upwardly inclined plates connecting the intermediate portions of the first mentioned plates and means for supporting the hopper upon a car independently of the ice tanks.

6. In a hopper for refrigerator car tanks, a bracing frame adapted to extend crosswise of a car and including spaced longitudinal bars and other spaced bars spanning the first mentioned bars and secured thereto, the bars of the frame being adapted to engage ice tanks and hold them against movement in said car, upstanding hopper sides rising from the longitudinal frame bars and upstanding hopper plates extending between the longitudinal hopper sides and secured thereto and to cross bars.

7. A combined ice tank bracing frame and ice hopper for refrigerator cars, said frame including substantially parallel bars spaced to engage the front and rear walls of a set of ice tanks to hold them against movement in opposite directions, spaced cross bars spanning the space between and secured to the first mentioned bars and disposed to engage opposite side walls of the tanks to hold them against movement in opposite directions, and a hopper secured to and rising from the bracing frame.

8. A combined ice tank bracing frame and ice hopper for refrigerator cars, comprising a horizontal bracing frame including substantially parallel bars provided with depending flanges spaced to engage upright walls of ice tanks at the top thereof, cross bars spanning the space between the longitudinal bars and connected thereto and having depending flanges to engage other side walls of ice tanks at the top thereof, said flanges constituting means to prevent lateral movement of ice tanks at right angles to one another, and a hopper having walls secured to and rising from the longitudinal bars, and other hopper walls rising from and secured to cross bars and also secured to the first mentioned walls.

9. A combined ice tank bracing frame and ice hopper for refrigerator cars, comprising a horizontal bracing frame made up of spaced longitudinal angle bars with corresponding flanges depending therefrom, cross bars extending between and connected to corresponding ends of the longitudinal bars, channel bars extending between and connected to the longitudinal bars with flanges depending from the backs of the channel bars, and a hopper comprising opposite longitudinal side walls rising from and secured to the longitudinal bars, opposite end walls rising from the end cross bars and secured to the end portions of the longitudinal side bars, and intermediate walls rising from and secured to opposite sides of one of the channel bars and also secured to the inner faces of the longitudinal walls, each intermediate wall and the adjacent end wall defining a hopper.

10. The combination with a refrigerator car having a pair of spaced hatches for the introduction of ice therethrough, and a set of upright ice tanks having open tops spaced below and in reg-

istration with the hatches, of a combined ice tank bracing frame and ice hopper including spaced longitudinal bars extending transversely across the car beneath the hatches and terminally secured to parts of the car, end cross bars and intermediate cross bars extending between and secured to the longitudinal bars, each frame bar having a depending flange lapping top portions of the upright side walls of an ice tank, and a pair of hoppers each comprising walls rising from and secured to bar members of the bracing frame and rising to respective hatches.

11. The combination with a refrigerator car having hatchways through the roof thereof and a series of ice tanks within the car and beneath the hatchways, of a frame supported on the car and provided with means closing the open tops of the spaces between the ice tanks, and hoppers supported on the frame and communicating at their tops with the respective hatchways and at their bottoms with the respective ice tanks.

12. In a hopper for refrigerator car tanks, spaced outwardly and inclined sheets adapted to extend crosswise of the car below the hatches and above the ice tanks, inwardly and upwardly inclined plates connecting the end portions of the first mentioned sheets, outwardly and upwardly inclined plates connecting the interme-

diate portions of the first mentioned plates, and means for supporting the hopper at the longitudinal sides of the car independently of the ice tanks.

13. As a new article of manufacture, a hopper for connecting the hatchway of a refrigerator car with an ice tank, comprising a supporting frame having means for supporting the frame on a car independently of the ice tanks, and a hopper carried by the frame independently of the ice tank and open at its top and bottom for registration respectively with the bottom of a hatchway and the top of an ice tank.
